Primary Examiner — Eric Goodman*Assistant Examiner* — Clese Moore, Jr.*(74) Attorney, Agent, or Firm* — Global IP Counselors, LLP(57) **CLAIM**

The ornamental design for a steering wheel unit for an automobile, as shown and described.

DESCRIPTION

FIG. 1 is a front elevational view of a steering wheel unit for an automobile in accordance with our new design;

FIG. 2 is a rear elevational view thereof;

FIG. 3 is a top plan view thereof;

FIG. 4 is a bottom plan view thereof;

FIG. 5 is a left side elevational view thereof;

FIG. 6 is a right side elevational view thereof;

FIG. 7 is a front perspective view thereof; and,

FIG. 8 is a rear perspective view thereof.

The broken lines shown in FIGS. 2, 4 and 8 are boundary lines and form no part of the claimed design. The area circumscribed by these boundary lines has been removed from the disclosure and does not illustrate a part of the steering unit.
